UNITED STATES PATENT OFFICE.

GEORGE R. BACK, OF GOTHENBURG, NEBRASKA.

DESIGN FOR A FLY BRUSH OR BAT.

SPECIFICATION forming part of Design No. 26,497, dated January 5, 1897.

Application filed October 28, 1896. Serial No. 610,157. Term of patent 14 years.

To all whom it may concern:

Be it known that I, GEORGE R. BACK, a citizen of the United States of America, residing at Gothenburg, in the county of Dawson and State of Nebraska, have invented and produced a new and original Design for a Fly Brush or Bat, of which the following is a specification, reference being had to the accompanying drawings, that illustrate the form thereof and the materials of which it is constructed.

Figure 1 shows a face view of the brush, and Fig. 2 an edge view.

The letter A designates a piece of flexible woven-wire fabric of quadrangular shape that has its continuous edge doubled inward to produce a border B, as required, to prevent the wire threads from unraveling.

C represents a handle made of a single length of wire doubled at its center and 20 twisted together at the point D to produce a loop and handhold E. The parallel end portions are passed through the wire fabric and then bent backward to produce forms H. The ends are soldered fast at the points where 25 they come in contact with the body of the wire and also soldered fast to the flexible wire fabric A.

What I claim is—

The design for a fly brush or bat substantially as shown and described. 30

GEORGE R. BACK.
